UNITED STATES PATENT OFFICE

2,103,005

SEAMLESS GRAVE VAULT AND METHOD OF
FORMING IT

John H. Handley, Des Moines, Iowa

Application March 18, 1937, Serial No. 131,737

3 Claims. (Cl. 72—7)

This invention relates to grave vaults and particularly to grave vaults formed of concrete or equivalent artificial stone.

The general object of my invention is to provide a grave vault of concrete or equivalent material which is absolutely seamless and without joint. A vault that has any seam at all or any joint, though the joint may be caulked or otherwise filled or sealed, is open to disintegration because the elements eventually gain access to the interior of the vault through the seam or joint. The moment that air and water gain access to the interior of the vault, the vault is doomed to destruction.

Another object is to provide a seamless concrete vault which is reinforced by upper and lower reinforcing elements which have members extending longitudinally and transversely of the top, bottom, side and end walls of the vault and in which the top element is adapted to fit over and rest upon the bottom element, and in which the two elements have overlapping portions, these two elements being adapted to be disposed to entirely enclose the casket or the rough box within which the casket is placed, and to be entirely embedded in concrete when the material of the seamless vault is poured or tamped.

A further object is to provide a very simple method whereby this seamless vault may be formed.

Other objects will appear in the course of the following description.

My invention is illustrated in the accompanying drawing wherein:

Figure 1 is a vertical section through a grave vault constructed in accordance with my invention, the grave vault being in place within a grave.

Figure 2 is a section on the line 2—2 of Figure 1.

Figure 3 is a top plan view of the lower section of the reinforcement.

Figure 4 is an end elevation of both reinforcing sections.

The construction of the vault will be best understood by describing the manner in which the vault is formed. As soon as the usual grave is dug, six supporting blocks designated 10 are disposed on the bottom of the grave. These blocks may be stone, marble, cement or other like material, and preferably have a dimension of 4 x 6 x 2 in. One of these blocks is placed at each corner of the grave and a block on each side at the middle. Upon these blocks, the lower reinforcing element designated generally 11 is disposed. This consists of longitudinally extending reinforcing members 12 and transversely extending members 13, which are preferably of steel but may be made of any other suitable material, these members being interconnected with each other

in any suitable manner as by welding, brazing or the like. It is to be particularly noted that the transverse and longitudinal members 13 are upwardly extended at their ends and that the outermost reinforcing member 14 extends in the form of a rectangular frame. Upon the reinforcing element 11 there are disposed two or more V-shaped cross-bars 15 having their apices extending upward, these being disposed one at each end of the reinforcing element 11 but between the supporting blocks 10.

A preformed rough box designated generally 16 is provided which has been treated on the outside to fill all cracks, possible holes and pores of the wood with a water-proofing material such as asphalt, pitch, tar, paint, oil-cloth, cellophane or any other suitable material of this character. This box is, of course, provided with a removable cover 17. The box 16 is lowered into the grave and rests upon the V-shaped supports 15. The grave is then in condition for an interment. As soon as the casket is lowered into the rough box 16, the lid 17 is then put in place and secured and sealed. The whole rough box with the contained coffin is then raised by suitable equipment and green water-proof cement or concrete is mixed and poured into or disposed in the bottom of the grave covering the six supports 10 and embedding the bottom steel reinforcing element 11 within this concrete. This concrete base, which is designated 18, has a thickness of about 4 in.

The rough box 16 is then lowered into place with the casket therein, this outer box 16 acting as a form. The box rests upon the V-shaped members 15. When this has been done, a cage-like upper steel reinforcing element designated generally 19 is then lowered over the rough box onto the base 18 and inside of the outer upturned ends of the longitudinal and transverse reinforcing members. The upper reinforcing element 19 has a top portion, opposed side portions and opposed end portions, and is of sufficient cross-sectional area as to fit down over the box 16 and be spaced therefrom a suitable distance. The element 19 comprises upper and lower rectangular frame members of steel, wire, rod or other suitable material and designated 20. Transverse and longitudinal wires or rods 21 are engaged with the lower frame 20 and extend upward and over the upper frame 20 and are attached to each other and to these frame members 20 in any suitable manner as by brazing, soldering or the like. An open-bottomed cage is thus formed which constitutes the upper reinforcing element for the side walls and top of the concrete grave vault.

After the upper reinforcing element has been lowered into position with the lower portions of its side and end walls within the upturned ends of the elements 12 and 13, yokes 22 are disposed

over the ends of the upper reinforcing element of the cage, these yokes at their lower ends having inwardly turned hooks 23 which engage beneath the element 11. The lower ends of these 5 yokes are forced into the still plastic mass which forms the base 18.

Cement or concrete mixture having a formula preferably of 1, 1 and 2, mixed with water-proofing material is then poured into the opening of 10 the grave and completely covers the encaged rough box 17 to a depth which completely embeds the upper reinforcing element 19 within the concrete. The walls of the dug grave, of course, form the outer form for the concrete while the 15 box 16 with its lid 17 constitutes the inner form. This permits the complete enclosure of green concrete or cement to be formed in a few minutes time. This concrete will ripen and dry evenly as a unit without any seam anywhere. An appropriate name plate 24 has posts which are inserted within the concrete 25 which has been poured around the sides and over the top of the box 17 and preferably four bars of bronze or brass or other suitable material designated 26, are also 20 embedded in the concrete 25 over the top of the box, these four bars being disposed adjacent the corners of the concrete vault thus formed. These bars 26 are provided with eyes 27 whereby, if disinterment is desired, the vault may be 25 lifted out of the ground.

After a sufficient time, that is, after the concrete has sufficiently hardened and ripened, a board top 28 is placed over the top of the concrete 25 and then the grave is filled with dirt.

35 It is to be understood that I may use any artificial stone which may be suitable for the purpose and that by the term "concrete" as used in the appended claims, I intend to include any form of suitable artificial stone which is initially 40 plastic and may be poured or tamped around the rough box 16 and its cover. The reinforcing members which form the upper and lower reinforcing elements may be made of either bars, wire mesh, fencing material or any other appropriate reinforcing members, whether these are 45 welded, soldered, wired or otherwise connected with each other.

It will be seen that by my structure and by 50 my method of forming a grave vault, I provide a vault that has no seams and which, under no circumstances, will permit air or water to gain 55 access to the interior of the vault. It will be seen that my concrete vault has but few pre-formed parts. The reinforcing elements may be made very cheaply and when completely embedded in the plastic material entirely reinforces the whole area of the vault and prevents any possible chance of cracking, distortion or collapse. Furthermore, pressure of the earth against this 60 mass of heavy concrete, reinforced as it is, will not act to distort or collapse the vault nor will the vault be deformed, collapsed or cracked by upheavals or the action of frost or other ground disturbances. The inverted reinforcing "cage" 65 19 gives greatest possible strength to the vault and prevents the top from caving in. The pressure on the top of the vault is taken up by the sides of the vault pressing against solid earth walls and by the bottom frame which interlocks with the inverted cage reinforcement or cover.

A vault constructed in accordance with my invention can be easily disinterred and moved from the original grave to a new one. In view 70 of the fact that the vault is seamless, there is no

possibility of the escape of gases or other matter, or the entry of water, therefore, there will be no possible pollution of surrounding water, air or earth. The possibility of theft is reduced to a minimum as this type of vault cannot be broken into by grave robbers, without a tremendous amount of work and without the use of explosives. There is no possibility of removing a cover or dome as there is in two-part vaults and the removal of the casket by grave robbers.

10 It is obvious that the principle of my invention might be applied to different forms of vaults, and I do not wish to be limited to the specific form except as stated in the appended claims.

15 What is claimed is:—

1. A grave vault having integral top, bottom, end and side walls, a base reinforcing element disposed within the bottom wall and including longitudinal and transversely extending reinforcing members, an upper reinforcing element extending throughout and embedded within the top, end and side walls and comprising longitudinal and transversely extending reinforcing members, the base reinforcing element having upwardly turned end portions, the upper reinforcing element having side and end portions disposed within the upwardly turned end portions of the base element, and yokes arching over the upper reinforcing element and having hooks engaging with the lower reinforcing element, the yokes being embedded within the side and top walls of the vault.

2. A method of forming grave vaults within a dug grave consisting in disposing a base reinforcing element of transverse and longitudinal members in the bottom of the grave but spaced from the bottom, disposing transverse box supporting members upon the reinforcing element, filling concrete in the grave until the reinforcing element and the lower portion of the box supporting elements are entirely embedded, lowering a casket box onto the box supporting elements while the base is still in a plastic condition, disposing an open-bottomed reinforcing element over the box and resting upon the previously formed base, the reinforcing element having open-work top, side and end portions, pouring concrete over the box and between the sides and end walls of the box and the dug grave until the upper reinforcing element is entirely embedded within the concrete, allowing the concrete to harden, and filling in the grave.

3. A method of forming grave vaults within a dug grave consisting in disposing a base reinforcing element of transverse and longitudinal members in the bottom of the grave but spaced from the bottom, disposing transverse box supporting members upon the reinforcing element, filling concrete in the grave until the reinforcing element and the lower portion of the box supporting elements are entirely embedded, lowering a casket box onto the box supporting elements while the base is still in a plastic condition, disposing an open-bottomed reinforcing element over the box and resting upon the previously formed base, the reinforcing element having open-work top, side and end portions, pouring concrete over the box and between the sides and end walls of the box and the dug grave until the upper reinforcing element is entirely embedded within the concrete, inserting ring bolts within the still plastic concrete at the corners of the vault so formed, and filling in the grave.
